ROLLER SCREEN

Albert Lang, Berkeley, Calif.

Application October 13, 1933, Serial No. 693,460

12 Claims. (Cl. 156—39)

The present invention relates to an improved roller window screen and more particularly to a new and novel construction for a retractable roller screen and a controlling means for extending and holding the screen in any desired position within the limits of its travel.

An object of the invention is to provide a new and novel construction for a metallic window screen of the roll away type.

Another object of the invention is to provide an improved form of draw bar construction for a window screen of the above character.

Another object of the invention is to provide an improved form of guide and holding means for a spring retracted roll type window screen.

Another object of the invention is to provide, in combination with a spring retracted window screen, a latching means therefor which may be released by applying a downward or screen drawing pressure thereupon.

Another object of the invention is to provide, with a roll screen of the type having guide means disposed along the path of its travel, a novel form of latching means which will cooperate with the guide means to center and hold the end of the screen in the guide means.

In the prior art, to which the invention relates, it is the practice to provide a screen of the roll away type with independently operated latching means at each side thereof. Such a screen requires two hands to adjust it and cannot be conveniently operated when the upper limit of its travel is above the normal reach of the operator or over approximately five feet from the floor. This means that such a screen cannot be raised to the full extent of the window frame, to which it is applied, unless the operator stands upon a stepladder, chair or the like. Therefore, it is a further object of the present invention to provide a new and novel form of screen holding and drawing means that can be operated by a pull cord and which will facilitate a rolling up or extension of the screen, throughout the full length of a window frame, without resort to the use of a stepladder or chair, as suggested above.

In carrying out this invention the screen is made entirely of metallic parts of novel construction which may be secured together in a simple manner without the use of rivets, solder or welding. The screen is also provided with an improved guide means and a detent cooperating therewith which can be operated by a simple downward pressure, as by means of a pull chain or cord, to release the same and thus

permit a retraction or an extension of the screen without the application of any other manual force.

For a better understanding of the present invention reference should be had to the accompanying drawing in which:

Figure 1 is a perspective view showing a screen constructed in accordance with the invention and mounted in a window frame,

Figure 2 is a fragmentary perspective front view showing the draw bar construction contemplated by the invention,

Figure 3 is a fragmentary perspective back view with parts broken away to show the draw bar assembly and a detent rod carried thereby,

Figure 4 is a perspective view of the detent rod assembly,

Figure 5 is a fragmentary view, partially in section, showing the manner of securing an actuating spring and an operating member to the detent rod,

Figure 6 is a full size fragmentary sectional view taken at the center of the draw bar illustrated in Figure 2, and

Figures 7, 8 and 9 show modified forms of a draw bar assembly and screen latching means constructed in accordance with the invention.

A roll away screen of the type contemplated by this invention may be mounted either upon the inside or the outside of the window frame. In Figure 1 of the drawing the screen, designated by the numeral 10, is shown as mounted inside of the window. This is the preferred arrangement as the screen will then be protected from inclement weather when the window is closed. The screen 10 is shown as suspended within the window frame from a screen retracting spring roller which is rotatably supported within a roller concealing housing 11. Extending downwardly from the housing 11 and along each cheek of the window frame there is a channel or guide 12 into which projects the edges of the screen and the ends of a draw bar 13 secured at the lower end of the screen. With this arrangement the screen 10 may be extended to the full length of the window frame and thus provide full protection when the window is opened from either the top or the bottom, or from both its top and bottom.

The features of the present invention, which are considered to be particularly novel, appertain to the screen guide means, its draw bar construction and a latching means which will cooperate with a spring retracted roller screen

to hold the screen in any desired position with the screen under tension.

For a more detail description of the various parts thereof, reference is made to the remaining figures of the drawing. From an inspection of Figure 2 of the drawing it will be seen that the draw bar 13, secured to the lower end of the screen 10, carries a centrally located detent operating means 14 to which there is attached a pull cord or chain 15. As illustrated in Figures 3 and 6 of the drawing, the draw bar 13 is constructed of two transversely extending members which will be designated as a front member 16 and a back member 17. These members 16 and 17 are formed of sheet metal bent so as to interlock with each other and are secured in cooperating relation by means of end clips 18 which are pressed thereupon so as to clamp the two members into close engagement with each other. The clips 18 may be secured upon the ends of the members 16 and 17 by any suitable means. The preferred arrangement is to depress a portion of one of the sides of these clips, as shown at 19, into holes properly located in the ends of the members 16 and/or 17. This provides a simple and easily assembled draw bar which can be made up without the use of rivets, welding or the like. When the clips 18 are thus secured upon the ends of the draw bar 13 they will act as a shoe or runner that will slide freely between coating flanges carried by the screen guides 12 and, in conjunction with the detent means, to be hereinafter described, firmly hold the end of the screen against rattling.

In its preferred form the front member 16, of the draw bar 13, is provided, as shown in Figure 3 of the drawing, with a simple flange along its upper edge and a similar but larger flange at its lower edge. These flanges stiffen the front member 16 and impart rigidity to the draw bar 13. The flange at the lower edge of the front member 16 is formed by bending the sheet metal outwardly and then back and up in spaced relation with the rear side thereof and finally downwardly to form a transversely extending recess into which a strip of felt 20, that will engage the window sill, may be disposed. The back member 17, of the draw bar 13, is attached to the screen 10 by folding the lower edge of the screen material about a flange provided along the upper edge of the back member and then pressing the screen and flange together into clamping engagement with each other. The back member 17 also has a groove or recess extending lengthwise thereof just below the flange by which it is secured to the screen. This groove, in conjunction with the front member 16, forms a seat or bearing for a detent operating rod 21 that extends completely across the draw bar 13. When the back member 17 has been attached to the screen 10 and the detent operating rod 21 is placed into the groove in the member 17, the lower edge of the member 17 can be inserted between the back of the front member 16 and the upturned portion thereof. The members 16 and 17 can then be firmly secured together to complete the draw bar 13 by applying the end clips 18.

As shown in Figure 4 of the drawing, the detent operating rod 21 has its ends turned back as a hook to form a detent 22 at each end thereof that will cooperate with the channels or guides 12, as will hereinafter appear, and at its center the detent operating rod 21 has two offset portions 23 to which the operating means 14

is attached. When the front member 16 and the back member 17 of the draw bar 13 are assembled together, as suggested above, with the detent operating rod 21 therebetween, the offset portions 23 of the detent rod 21 will extend through a hole in the member 16 and project out at the front of the draw bar 13. The detent operating means 14 can then be secured to the detent rod 21 at the front of the screen. This arrangement presents a neat appearance as it places the detents 22 and the operating rod 21 in back of the draw bar 13 and leaves only the detent operating means 14 in view at the front of the draw bar, where it can be conveniently operated by a simple downward screen drawing pressure of the hand or by a pull cord. The detent operating means 14 may be formed to any suitable shape which will facilitate its attachment to the rod 21, or it may be omitted entirely. In this latter event the detent rod 21 need have only one offset portion 23 which will extend out sufficiently far in front of the draw bar 13 to be engaged by the operator's thumb and/or carry the pull cord or chain 15.

As illustrated in Figures 4 and 5 of the drawing, the detent operating means 14 is formed of a single piece of stamped sheet metal having a recess 24 into which the offset portions 23 may project. It also has a thumb or finger rest 25 upon which pressure may be exerted in operating the detents 22. The recess 24 has a width just sufficient to receive the offset portions 23 upon the detent operating rod 21. When the means 14 is in position upon the detent operating rod 21, as shown, it may be secured thereto by prick punching or upsetting the sides of the recess 24, as at 26, so as to interlock portions thereof with the offset portions 23. At the lower side of the recess 24 the means 14 has a pair of opposed ears 27 between which a spring barrel 28 and a coiled spring 29 are disposed. One end of the spring 29 engages the detent operating means 14 and at its other end it is adapted to engage the front surface of the draw bar 13 so as to provide an upward bias upon the detent operating means 14 and consequently a downward bias upon the detents 22.

In order to render the above described construction most effective it is desirable that the channels or guides 12 be so shaped that they will cooperate to a maximum degree with the draw bar 13 and the detents 22. A preferred form of guide, for a screen equipped as above, is illustrated in Figures 2, 3 and 6 of the drawing. In these figures of the drawing each of the guides 12 is formed by bending a piece of sheet metal into a semitubular shape and of rectangular cross section. As here shown, the guides 12 have narrow openings extending lengthwise thereof and inturned or reentrant flanges 30 formed along one side of the narrow openings. The inturned or reentrant flanges 30 are adapted to provide surfaces over which the clips 18 may freely slide when the detents 22 are released and against which they will be firmly held when the detents 22 are biased into their screen holding position. Upon the back of each of the flanges 30 there is a plurality of vertically spaced protuberances 31 that are adapted to be engaged by the hooked ends of the detents 22 and hold the screen in its extended position against the action of the screen recoiling spring carried by the roller, within the housing 11, from which the screen 10 is suspended.

As shown, the detents 22 are formed by bending back the ends of the detent operating bar 21 so as to provide oppositely projecting hooks upon each end thereof. When the detents 22 are formed in this manner, and used in guides 12 of the character described above, they will, in addition to acting as a latching means for the screen 10, also interlock with the flanges 30 of the guides 12 to thus center the draw bar 13 and the screen 10 between the guides and prevent the draw bar from being accidentally or deliberately removed from the guides 12 when the screen 10 is being extended or retracted.

While I have described the invention in its preferred form, it is to be understood that the essential features and advantages thereof may be attained in other ways as, for instance, by constructing the guides, draw bar and detents in accordance with the showings made in Figures 7, 8 and 9 of the drawing which will now be described.

In Figure 7 there is shown a channel guide 32 of rectangular cross section having a simple in-turned flange 33 in which there is formed a plurality of vertically spaced depressions 34. The draw bar, designated by the numeral 35, is constructed of two transversely extending pieces of sheet metal secured together by clips 36 which are pressed over the ends thereof, as is the case in the draw bar 13. In this construction there is a detent bar 37 which, instead of having hook shaped detents, has its ends simply turned up to form detents 38 that will engage the depressions 34 in the flange 33 of the channel guide 32. The detents 38 are here shown as biased into the depressions 34 by a small spring 39 that engages a loop 40, formed centrally upon the detent bar 37, which extends out through the draw bar 35, where it can be operated by a downward pressure or by a pull cord.

In Figure 8 of the drawing there is illustrated a draw bar 41 and a channel guide 42 formed substantially similar to the draw bar and guide channel shown in Figure 7. In this embodiment a detent operating rod 43 is formed in a manner similar to the detent operating rod 21 described above and illustrated in Figure 4 of the drawing. The detent operating rod 43, instead of having detents that will engage protuberances upon the back of the guide channel flange, has inturned or hooked ends 44 that operate upon a resilient detent member 45 which engages recesses formed in a flange 46 on the channel guide 42. In this construction, like those previously described, the detents can be operated by a simple downward pressure applied at the center of the draw bar 41.

In Figure 9 of the drawing there is shown a further modification of the present invention, wherein the screen can also be operated by a simple downward pressure applied centrally upon the screen draw bar or by a pull cord. As here illustrated the screen guide, designated by the numeral 47, is of a different shape, in that it has a trackway 48 formed upon one flange and with protuberances 49 formed upon an opposite flange. In this arrangement a draw bar 50 is formed from one piece of metal and has projecting feet or runners 51 at the ends thereof which engage the trackway 48. The upper edge of the draw bar 50 is secured to the screen 10 by pressing oppositely disposed parts thereof over a rod 52 about which the screen material is wrapped. Another difference is that a detent

operating rod 54 having detents 53 is mounted upon the front side of the draw bar 50 instead of at the back, as is the case in the other structures. The detents 53 are biased into engagement with the protuberances 49 by a small leaf spring 55 at each detent. These springs 55 can be overcome by a downward pressure exerted upon a centrally located forwardly projecting portion 56 of the detent rod 54 and as a result a screen constructed in this manner can also be operated by a downward screen drawing movement applied by the hand or through a pull cord.

The operation of a screen constructed in accordance with this invention should be obvious from the above description. However, there are a number of features, the functions and operations of which should be explained further. When the screen 10 is equipped with a draw bar 13, of the type illustrated in Figures 1 to 6 of the drawing, the screen can be drawn by simply applying a downward pressure upon the thumb rest 25 of the detent operating means 14. In this operation the pressure thus exerted upon the means 14 will rotate the detent operating rod 21 and move the detents 22 out of engagement with the protuberances 31 upon the guides 12 and permit the shoes or runners, formed by the clips 18, to slide freely over the flanges 30. When the operator releases the detent operating means 14 the spring 29 will rotate the rod 21 in a reverse direction and cause the detents 22 to move against the rear side of the flanges 30 and into engagement with the protuberances 31. It should here be pointed out that the disposition of the detents 22 upon the detent operating rod 21 is such that the coiled spring 29 will be assisted in its action by the screen retracting spring to which the screen 10 is secured. Under these conditions the screen retracting spring will exert an upward pull upon the detents 22 and, as a result of the horizontal component of force resulting from the angular displacement of the detents 22 from the axis of the detent operating rod 21, cause the clips 18 to bear against the flanges 30 and thus clamp the draw bar 13 in place and prevent a rattling of the screen by wind or vibration.

The above clamping action will also be found in the embodiments of the invention illustrated in Figures 7 and 8 of the drawing. In these structures the clamping action will be accomplished by the screen retracting spring, but in a different manner. When the detents 38 and 45 of Figures 7 and 8 are in engagement with their respective recesses, in the guides 32 and 42, the screen tension exerted by the screen retracting spring will cause the clips 18, at the ends of the draw bars 35 and 41, to move against the front flanges of the guides 32 and 42 and thus, with the detents 38 and 45, wedge the draw bars 35 and 41 into non-rattling engagement with their respective guides.

In the embodiment of this invention illustrated in Figure 9 of the drawing the draw bar 50 is provided with projecting feet 51 which are disposed in a reasonably snug groove 48 formed in resilient material that will provide a sufficient tightness to prevent a rattling of the screen, without interfering with its free movement.

An important aspect of this invention is that it provides a screen which can be operated with one hand and/or by a pull cord. When a pull cord is attached to the detent operating means

the screen can be easily operated to any height in a simple and convenient manner.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves, in view of this broad disclosure, to persons skilled in the art. It is believed that this invention is broadly new and it is desired to claim it as such so that all such changes as come within the scope of the appended claims are to be considered as part of this invention.

Having thus described my invention, what I claim and desire to secure by Letters Patent is—

1. In an improved roll screen, the combination of a pair of spaced parallel guides, a spring retractable roll screen disposed between said guides, a draw bar at the end of said screen for drawing it along between said guides, a rod extending along and rotatably mounted upon said draw bar having its ends bent to form detents which will cooperate with said guides and hold said roll screen in an extended position, and means operable by a downward screen drawing movement for rotating said rod and releasing said detent means.

2. In a screen of the character described, the combination of a pair of spaced parallel guides, a spring retractable roll screen disposed between said guides, a draw bar at the end of said screen for drawing it along said guides, a rotatably mounted rod extending throughout the length of said draw bar, means at each end of said rod cooperable with said guides forming a detent for holding said roll screen in an extended position in said guides, and means at the center of said rod operable by a downward screen drawing movement for rotating said rod and releasing said detent means.

3. In an improved roll screen, the combination of a spring retractable roll screen, guide channels into which the edges of the screen are disposed having a reentrant flange upon one side thereof, a draw bar secured across the end of said screen and extending into said guide channels, a rotatable longitudinally extending rod carried by said draw bar having its ends bent around and cooperating with the adjacent reentrant flange upon said guide channels for centering the screen between said guide channels, and means for biasing said rod in a position whereby its ends will engage said reentrant flange and hold the screen in an extended position.

4. In an improved roll screen, the combination of a spring retractable roll screen, guide channels disposed along the sides of said screen having a reentrant flange upon one side thereof, a draw bar secured across the end of said screen extending into said guide channels and engaging one side of the respective reentrant flange, a rotatable rod carried by said draw bar having its ends bent around engaging the other side of the respective reentrant flange upon said guide channels for centering the screen between said guide channels, and means for biasing the ends of said rod into clamping engagement with the respective reentrant flange.

5. The combination of a spring retractable screen, a guide at each side of said screen, a draw bar secured across the end of said screen

and extending into said guides, a rotatable detent operating rod carried by said draw bar, a detent at each end of said rod cooperating with the respective guide for holding said screen in an extended position, means intermediate the ends of said rod and located at the front of said draw bar forming a lever upon said detent operating rod, and a pull cord attached to the lever formed by said means for rotating said detent operating rod and raising and lowering said screen.

6. The combination of a spring retractable screen, a guide channel at each side of said screen, a draw bar secured across the end of said screen and extending into said guide channels, a detent carrying bar secured against and extending along the back of said draw bar, a detent upon each end of said detent carrying bar cooperating with said guide channels for holding said screen in an extended position, and means projecting through said draw bar to the front thereof having a pull cord attached thereto for operating said detents and raising and lowering said screen.

7. A guide for a spring retracted metallic screen, said screen carrying a detent adjacent the end thereof, said guide comprising a single sheet of metal bent to a substantially rectangular form and having its meeting edges flanged inwardly and disposed in spaced relation with each other to form a guide for the edge of the screen, one of the flanges being disposed substantially centrally of the rectangular form, and detent retaining means upon said latter flange which will cooperate with said detent to hold the screen in an extended position.

8. A guide for a spring retracted metallic screen, said screen carrying a detent adjacent the end thereof, said guide comprising a single sheet of metal bent to a substantially rectangular form and having its meeting edges flanged inwardly and disposed in spaced relation with each other to form a guide for the edge of a screen, one of the flanges being disposed substantially centrally of the rectangular form and having protuberances formed thereupon by upsetting the flange which will cooperate with said detent to hold the screen in an extended position.

9. In a draw bar for a roll screen or the like, the combination of a transversely extending channel like member having its lower edge bent up in spaced relation with the back surface thereof, a second member having its upper edge crimped to the end of a screen material and its lower edge disposed in the space between the back of said channel like member and the bent up edge thereof, and guide channel engaging clips secured in clamping engagement over the ends of said channel like member and said second member for securing and holding said members together.

10. In a screen device, the combination of a pair of spaced parallel guides between which the screen may move, a transversely extending channel like member adapted to extend into said guides, a second member having its upper edge crimped to the end of a screen material disposed against the back of said channel like member, and a guide engaging clip secured in clamping engagement over the ends of said members forming the sole means for holding them together.

11. A draw bar and detent construction for a roll screen of the retractable roller type operating between spaced guides, comprising a trans-

versely extending member having a length substantially equal to the width of the screen, a second transversely extending member disposed in back of said first member, a detent operating rod disposed between and projecting at the ends of said members having its ends turned up to form detents which are engageable and cooperable with the spaced guides at the edges of the screen, and a metallic clip pressed over the ends of said first and second members for securing them together over the detent operating rod and forming a runner at each end of the draw bar which will slide freely in the spaced guides when the detents are disengaged and cooperate with the detents to clamp the draw bar to the guides when the detents engage the guides.

12. In a roll screen of the spring retractable

type, the combination of spaced screen guides between which the screen is adapted to slide, each of said guides having a flange extending parallel with the plane of the screen, a draw bar at the end of the screen having a runner at each end thereof adapted to engage one side of the flange carried by the associated guide, detent means carried by said draw bar bent around the respective flanges and adapted to engage the other side of said respective flanges, and spring means acting upon said detent means to bias them into engagement with said flanges, whereby the runners at the ends of said draw bar will be clamped against the flanges upon which they slide.
